CLAIM

The ornamental design for a vertical backgammon board, substantially as shown.

DESCRIPTION

FIG. 1 is a perspective view of the vertical backgammon board, this view looking at the right front corner thereof and showing my new design.

FIG. 2 is a top plan view thereof.

FIG. 3 is a bottom plan view thereof.

FIG. 4 is a right side elevation thereof.

FIG. 5 is a front elevation thereof.

Fig. 1.

Fig. 2.
